UNITED STATES PATENT OFFICE.

ARTHUR H. BAKER, OF JACKSONVILLE, FLORIDA.

TURPENTINE-CONDENSER.

1,179,791.

Specification of Letters Patent. Patented Apr. 18, 1916.

Application filed December 4, 1915. Serial No. 65,103.

To all whom it may concern:

Be it known that I, ARTHUR H. BAKER, a citizen of the United States, residing at Jacksonville, in the county of Duval and 5 State of Florida, have invented new and useful Improvements in Turpentine-Condensers, of which the following is a specification.

In the process of distilling, there is a certain amount of vapor that escapes from the 10 condensing worm with the condensed spirits, and passes into the atmosphere and is lost.

My invention is designed to provide an auxiliary condenser which is connected with the tail of the ordinary condensing worm 15 and receives and holds this escaping vapor, condenses it and at the same time cools the spirits before reaching the air, so as to prevent the losses which occur from the evaporation into the air of a portion of hot 20 spirits which commonly occur.

The invention is further designed to provide a turpentine condenser which is simple of construction, reliable and efficient in operation, and which may be operated without 25 adding to the normal cost of production.

The invention consists of the features of construction, combination and arrangement of parts herein fully described and claimed, reference being had to the accompanying 30 drawings in which:—

Figure 1 is a view in side elevation showing the application of the invention to a turpentine still. Fig. 2 is a top plan view on an enlarged scale of the condensing tank, 35 the cover thereof being removed to disclose the arrangement of the condensing drums therein. Fig. 3 is a perspective view of the drums removed from the tank. Fig. 4 is a sectional perspective view through the 40 drums and showing the water supplying connections. Fig. 5 is an inverted sectional perspective view of one of the drums.

Referring to the drawings, 1 designates a still kettle, 2 a still worm or condenser, 45 and 3 my improved auxiliary condenser, which is connected with the tail of the worm 2.

As shown the condenser 3 comprises a water tank or receptacle 4, receiving the condensing elements of the auxiliary condenser, 50 which elements consisting of drums and connecting pipes are normally submerged in the water contained in the tank and cooled thereby. In practice, the two condensers may be 55 cooled by the same body of water, but this is not essential.

The condensing elements arranged within the tank 4 consist of a pair of receiving or primary drums 5 and 5^a and a pair of delivery or secondary drums 6 and 6^a. The drum 5 of the receiving pair is provided at one side with an inlet pipe or tube 7 which is connected with the tail end of the worm 2 and receives the spirits, vapor and water of condensation therefrom. The tank 5 is 60 connected with the tank 5^a by upper and lower connecting tubes or pipes 9 and 10, and the drum 5^a is connected with the drum 6 and the drum 6 with the drum 6^a through similar pipes or tubes, the final drum 6^a 65 having at its top an air discharge outlet 11 and a spirits discharge outlet 12. The pipes 9 connect the upper or vapor spaces of adjoining drums and the pipes 10, the lower or condensates containing spaces of the drums, 70 and these pipes are preferably made rectangular or flat in cross section so as to expose as much surface to the water as possible for a cooling action.

Each drum comprises a cylindrical vessel 80 13 within the body of which is arranged a condensing dome 14. This dome 14 is of less diameter than the vessel 13 and extends upwardly thereinto to a point just below the horizontal center of said vessel 13 and in 85 substantial alignment with the condensates discharge pipe or tube 10. The interior of the dome 14 which is closed against communication with the vessel 13 is filled with water, and thus presents an increased area of 90 cooling surface within the receptacle 13 to promote and increase the condensing action.

Extending transversely of the receptacle 13 is a partition 15 which projects across the top of the dome 14 and extends upward 95 to a level between the level of the pipes 9 and 10, said partition having at its ends depending portions which project down into the annular space between the side walls of the vessel 13 and drum 14 and thus divides 100 the lower portion of the drum into inlet and exit chambers 16 and 17. These chambers are in communication at their lower ends through openings 18 between the bottom wall of the receptacle 13 and the depending portion of the partition 15, and are also in communication above said partition.

The inlet chamber 16 of the first drum 5 of the series is in communication with the pipe 7 through which the spirits, vapor and 110 water of condensation from the still 2 flows thereinto. The pipe 7 is arranged opposite

and in line with the partition 15, which serves as a baffle against which the entering fluids strike, the vapor rising and passing over the partition into the upper portion 5 or vapor containing space of the discharge chamber 17 while the spirits and water of condensation flow downwardly and pass through the openings 18 from the chamber 16 to the chamber 17, the result being that 10 the spirits and water of condensation are cooled to a further extent, while the vapor contained in the top portion of the drum is also cooled and condensed to a greater or less extent.

15 Any portion of the vapor contained in each drum which is not condensed flows through the pipe or tube 9 into the next drum and is wholly or partially condensed therein, the arrangement being such that 20 all of the vapor will be condensed in the successive drums before the discharge of the condensates from the drum 6^a, while the spirits and water flow from the spirits and water containing spaces of each drum 25 through the pipe or tube 10 to the equivalent spaces of the other drums in turn, whereby the spirits are continually reduced in temperature until discharged, thus affecting a reduction of the temperature to 30 such a degree as to prevent the flashing of any of the spirits into vapor when it is finally discharged from the condenser into the atmosphere.

It will be evident from the foregoing that 35 the condensation of the vapor and cooling of the spirits and water will continue until all of the vapor is condensed and the products collected in the final drum 6^a, from which the air discharges through the pipe 11 and 40 from which the spirits and water of condensation are drawn off through the pipe 12 for subsequent separation in any of the well known ways and storage of the spirits for final disposition. It will be evident that as 45 the drums of the auxiliary condenser are thoroughly cooled the vapors escaping from the spirits will be condensed and recovered, thus preventing their loss, while at the same time the spirits will be cooled to such a degree 50 before discharge as to prevent evaporation of the volatile constituents thereof on coming into the air. A considerable portion of the spirits is saved, and greater economy 55 secured, in the distillation of turpentine, in large plants.

The cooling water may be supplied to the apparatus in any preferred manner, but in the present instance I have shown a valve water supply pipe 18 which communicates 60 with the tank 4, from which the water discharges through a valved outlet 19, so as to maintain a gradual and uniform circulation of the water. The pipe 18 is connected by cross pipes 20 with nozzles or injectors 21 which extend upwardly into the domes of

the drum, so as to discharge cooling water directly into the space bounded by each drum, whereby a greater efficiency of cooling action is secured. A vent outlet 22 extends upwardly through each drum, and communicates at its lower end with the dome and projects at its upper end through the top of the drum into the tank, said upper end of the vent pipe being provided with a valved outlet or vent cock 23, so as to establish an upward circulation of water through the drum, thus keeping the body of the drum, interiorly as well as exteriorly, cooled to a desired low temperature.

I claim:—

1. An auxiliary condenser for turpentine distilling apparatus including a plurality of communicating condensing vessels, each partitioned to provide spaces for the condensates and vapor, the like spaces of said vessels communicating with each other, the first vessel of the series being provided with an inlet for the condensates and vapor, and the last vessel of the series being provided with separate outlets for the condensed spirits and 90 the air.

2. An auxiliary condenser for turpentine distilling apparatus comprising a plurality of condensing receptacles, each having a dome-shaped portion extending upwardly 95 into the base thereof and of less diameter than the vessel, and a partition separating the lower portion of the vessel containing said dome-shaped portion from the upper portion of the vessel, so as to provide liquid and vapor containing spaces, and means connecting the spaces of the vessels with each other.

3. An auxiliary condenser for turpentine distilling apparatus comprising a plurality of condensing vessels, each having a condensing dome extending upwardly thereinto from the bottom of the vessel to a point about midway of the height thereof, said dome being of less diameter than the vessel, 105 a partition extending above the dome and separating the vessel into a lower condensates receiving space and an upper vapor receiving space, and an inlet for the spirits and vapors connected with the first vessel of the series, conductors connecting the condensates and vapor receiving spaces of the vessels of the series, and outlets from the condensates and vapor containing spaces of the last vessel of the series for the discharge 110 of the spirits and air from the condenser.

4. An auxiliary condenser for turpentine distilling apparatus comprising a series of condensing vessels, each having a hollow condensing dome extending upwardly thereinto from the bottom thereof, and of less diameter than said vessel, and having a partition separating the lower portion of the vessel into spaces to a point above the dome, whereby lower and upper condensates and 125

vapor containing spaces are provided, an inlet to the first vessel of the series disposed above the level of the dome and in line with the upper portion of the partition, pipes or 5 tubes connecting like spaces of the vessels, and outlets from the last vessel of the series for the spirits and air.

5. An auxiliary condenser for turpentine distilling apparatus comprising a series of 10 condensing vessels, each having a condensing dome of less diameter than the vessel extending upwardly into the bottom thereof to a point about midway of the height of the vessel, a partition extending at diametrically 15 opposite sides and across the top of the dome and dividing the lower portion of the vessel so as to provide lower condensates receiving spaces and upper vapor receiving spaces, said condensates receiving spaces being in 20 communication with each other, flat conducting pipes between like spaces of the vessels of the series, an inlet for the passage to the first vessel of the series of the conden-

sates and vapor from the condenser of the distilling apparatus, and outlets from the 25 last vessel of the series for the discharge of the spirits and air respectively.

6. An auxiliary condenser for turpentine distilling apparatus comprising a water tank, a series of condensing drums in said 30 tank, one drum of the series having a vapor inlet and another a spirits outlet, said drums being in communication with each other and each drum having a dome extending upwardly therein from the bottom thereof, 35 valved water conductors extending upwardly from the domes through the drums, and water supply nozzles projecting into the domes.

In testimony whereof I affix my signature 40 in presence of two witnesses.

ARTHUR H. BAKER.
